CLAIM

The ornamental design for a hand held shower head, as shown and described.

DESCRIPTION

FIG. 1 is a perspective view of a hand held shower head showing my new design, portions shown in broken lines forming no part of the invention;

FIG. 2 is a right side view thereof, the left side being a mirror image of the right side;

FIG. 3 is a top view thereof;

FIG. 4 is a bottom view thereof;

FIG. 5 is a front view thereof; and,

FIG. 6 is a rear view thereof.
